US0D1103902S

(12) **United States Design Patent** (10) **Patent No.:** **US D1,103,902 S**
(45) **Date of Patent:** **** Dec. 2, 2025**

(54) **SOLAR TOWER**

(71) Applicants: **Louis Fredrick Kiefer, III**, Nashua, NH (US); **Jennifer Kiefer Chesnell**, Mason, NH (US); **Louis Fredrick Kiefer, IV**, New London, NH (US)

(72) Inventors: **Louis Fredrick Kiefer, III**, Nashua, NH (US); **Jennifer Kiefer Chesnell**, Mason, NH (US); **Louis Fredrick Kiefer, IV**, New London, NH (US)

(**) Term: **15 Years**

(21) Appl. No.: **29/823,928**

(22) Filed: **Jan. 20, 2022**

(57) **CLAIM**

The ornamental design for a solar tower as shown and described.

DESCRIPTION

FIG. 1 is a perspective view of a first embodiment of a solar tower showing our new design;

FIG. 2 is a front-side, right-side, left-side and back-side view of FIG. 1;

FIG. 3 is a perspective view of a second embodiment of a solar tower showing our new design; and,

FIG. 4 is front-side, right-side, left-side and back-side view of FIG. 3.

The broken lines shown represent portions of the solar tower that form no part of the claimed design.

1 Claim, 4 Drawing Sheets
